UNITED STATES PATENT OFFICE.

CARL G. SPRADO, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

CIRCULATING SYSTEM.

Application filed July 19, 1926. Serial No. 123,586.

This invention relates in general to improvements in the art of circulating fluids, and relates more specifically to an improved circulating system for the cooling fluids in the jackets of prime movers such as internal combustion engines.

An object of the invention is to provide an improved circulating system which is simple, efficient and automatic in operation.

- 10 Another object of the invention is to provide improved means for effecting thorough circulation of the cooling medium in the jackets of prime movers such as internal combustion engines. A further object of 15 the invention is to provide an improved method of equalizing the temperatures of the cooling water or other medium in jackets or the like, by causing all portions of the cooling medium to constantly travel 20 along a predetermined path, and by supplying and delivering regulable quantities of the medium to and from the jacket. These and other objects and advantages of the invention will appear from the following description.

A clear conception of an embodiment of the invention and of the operation of systems constructed in accordance therewith, may be had by referring to the drawing accompanying and forming a part of this specification in which like reference characters designate the similar parts.

The single figure of the drawing illustrates a transverse vertical section through a gas engine cylinder embodying the improvement.

The gas engine cylinder to which the invention has been specifically applied by way of illustration, comprises an inner annular wall 4 having therein a liner 3 which surrounds the combustion chamber 2, an outer wall 5 surrounding and spaced from the inner wall 4 by means of radial ribs 6 to form an annular jacket space 7, and a plurality of inlet and exhaust pockets 8, 9 respectively spanning the jacket space 7 adjacent to the ends of the cylinder. The outer wall 5 is provided with a plurality of core supporting openings 10 which are normally sealed 45 by means of closure plates. A cooling medium supply pipe 13 communicates with the jacket space 7 at the bottom of the cylinder, and an ejector 11 is associated with the discharge end of the supply pipe 13 within the

jacket space. The ejector 11 has a perforated frusto-conical fluid directing discharge wall 12 which is preferably directed tangentially of and within the annular space 7. A cooling medium discharge pipe 14 communicates with the upper portion of the jacket space 7 and has a control valve 15 therein which may be either manually or thermostatically controlled. The end of the discharge pipe 14 is directed into a final discharge funnel 16 so as to provide a visible indication of the quantity of water passing through and from the jacket space.

During normal operation of the cooling system, the cooling medium, preferably water, enters the jacket space 7 at the bottom through the supply pipe 13 and the ejector 11 and the ejector discharge wall 12 directs the entering water tangentially with respect to the jacket space 7. The entering water by virtue of its high velocity draws other water from within the jacket through the perforations of the wall 12 and produces a thorough circulation of the cooling medium entirely about the inner wall 4. By properly setting the control valve 15, the quantity of cooling medium discharged from the jacket space 7 through the pipe 14 may be effectively controlled, and the temperature of the jacket water may thus be accurately regulated. The inlet of cooling water may obviously be effected through one of the holes 10, if so desired, and several supply pipes 13 and ejectors 11 may be provided in case more rapid circulation of the cooling medium within the jacket, is desired. It will be apparent that the invention provides simple and efficient means for automatically and effectively equalizing the temperatures of the cylinder jacket water, with the aid of the diffuser or ejector 11. This ejector by thoroughly circulating the cooling water entirely around the inner wall 4 and the liner 3, prevents the formation of local pockets within which undesirably heated water might accumulate. While the control valve 15 has been shown applied to the discharge pipe 14, this valve may obviously be applied to the supply pipe 13 if so desired.

It should be understood that it is not desired to limit the invention to the exact details of construction and operation of the system herein shown and described, for va-

rious modifications within the scope of the claims may occur to persons skilled in the art.

It is claimed and desired to secure by Letters Patent:

1. In combination, inner and outer walls spaced apart to provide a continuous annular jacket, means for admitting fluid to said jacket tangentially thereof and away from said inner wall, and means for controlling the quantity of fluid passing through said jacket.
2. In combination, inner and outer walls spaced apart to provide a continuous annular jacket surrounding said inner wall, means for admitting fluid to said jacket, an ejector for producing a flow of the admitted fluid through said jacket and entirely about said inner wall, and means for controlling the quantity of fluid passing through said jacket.
3. In combination, inner and outer walls spaced apart to provide a continuous annular jacket, means for admitting fluid to the lower portion of said jacket, means for causing said fluid to flow in the same direction entirely around said inner wall throughout said jacket, and means for controlling the delivery of fluid from an upper portion of said jacket.
4. In combination, inner and outer walls spaced apart to provide a continuous annular jacket surrounding said inner wall,

means for admitting fluid to the lower portion of said jacket, an ejector for causing the admitted fluid to travel throughout said jacket and entirely around said inner wall in the same direction, and a discharge pipe for said fluid at the upper portion of said jacket.

5. In combination, inner and outer walls spaced apart to provide a continuous annular jacket surrounding said inner wall, means for admitting fluid to the lower portion of said jacket, an ejector for causing the admitted fluid to travel throughout said jacket and entirely around said inner wall in the same direction, a discharge pipe for said fluid at the upper portion of said jacket, and means for controlling the quantity of fluid passing through said jacket.

6. In combination, inner and outer walls spaced apart to provide a continuous annular jacket surrounding said inner wall, means for admitting fluid to the lower portion of said jacket, an ejector for causing the admitted fluid to travel throughout said jacket and entirely around said inner wall in the same direction, a discharge pipe for said fluid at the upper portion of said jacket, and means associated with said discharge means for controlling the quantity of fluid passing through said jacket.

In testimony whereof, the signature of the inventor is affixed hereto.

CARL G. SPRADO.
